TELECOMMUNICATION SYSTEM

Gerald Deakin, New York, N. Y., assignor to International Standard Electric Corporation, New York, N. Y., a corporation of Delaware

Application June 21, 1943, Serial No. 491,628

10 Claims. (Cl. 179—27)

This invention relates to new and useful improvements in selecting arrangements for telecommunication systems and particularly to arrangements adapted for controlling successive selecting stages in automatic telephone exchange systems.

According to the present invention, a selecting arrangement is provided in which a broad band of potentials is provided to determine a first selecting stage. This broad band includes a plurality of narrow bands of potentials determinative of a second selecting stage. A plurality of first finder switches, e. g., are arranged to operate on any of the narrow bands, i. e., on the full width of the broad band to perform the first selection. Then second switches, e. g., a group of finders operate in accordance with the specific narrow band of potentials applied. For instance, the potentials selected by a first finder is extended to the banks of a plurality of second finders, each of which is arranged to select only one narrow band of potentials.

The selecting arrangement will find many applications to telecommunication systems. When applied to arrangements for identifying the designations of calling lines, a single identifying equipment provided in an exchange may be used simultaneously to identify a plurality of calling lines, as distinguished from prior selecting arrangements which permitted the identification of only one line at a time.

The invention will now be described in greater detail as applied to a telephone exchange system of the general type described in my co-pending application, Serial No. 484,184, filed April 23, 1943, and the application of H. F. Herbig, Serial No. 485,827, filed May 6, 1943, now Patent No. 2,354,682, issued August 1, 1944.

In the drawings which illustrate only as much of the system as is necessary for a clear understanding of the invention

Fig. 1 illustrates the general selecting scheme;

Fig. 2, the test circuit of one of the identification finders illustrated in Fig. 1;

Fig. 3, some uses of the identification arrangement illustrated in Figs. 1 and 2; and

Fig. 4, the application of the identification arrangement to out-trunking.

Referring now to Fig. 1, only the test terminals and test brushes are shown of switches used in the establishment of an automatic telephone connection of the type illustrated in my said co-pending application. A calling line may be connected with a called line over a first line finder, an A link, a second line finder, a B link and then over first, second, third, fourth, penultimate and final group selectors. However, in the present arrangement, no identification relay is provided in each A link, the t brush of each first line finder being connected direct to a terminal of a second

line finder. Each t wire of an A link in the same group of one hundred lines, is connected through a positively polarized rectifier S+ and a resistance R to a common starting relay Gs7. In Fig. 1, I have shown two groups of first line finders, group #1 serving lines 100 to 199 and group #5 serving lines 500 to 599.

A plurality of groups of first identification finders is provided, each group having terminal banks which are multiplied to the corresponding T terminals in the banks of the first line finders. One first identification finder is provided per one hundred subscribers' lines. These identification finders, just as the line finders and group selectors have, of course, the other customary terminals and cooperating brushes.

The t brushes of the first identification finders are connected to the terminal banks of second identification finders of which there is one per identification circuit. A test circuit like the brush of each second identification finder. The t wires of the six second identification finders are shown as connected to six different switching circuits. The first terminates at a wire chief's desk on key IK1 which is arranged to apply ground to the identification circuit and +48 volts to the T terminal of a first group selector. TB #2 of the second identification finder is connected with a relay IR1 forming part of the #1 toll trunk and adapted to apply ground to the identification circuit and +46 volts to the T terminal of a second group selector. The #3 test brush of the second identification finder is connected with the #2 toll trunk, the relay IR2 of which is arranged to apply ground to the identification circuit and +44 volts to a second GR. The #4 test brush of the second identification finder is connected with a relay IR3 of an automatic ticketing arrangement adapted to apply ground to the circuit and +42 volts to a second GR. The #5 test brush is connected with relay IR4, forming part of a special line service arrangement and which is adapted to apply ground to the circuit and +40 volts battery to a third GR. The #6 brush of the second identification finder is connected with a special portable test set which may be used by switchmen to determine the number of a calling subscriber or trunk. The key IK2 in the special test set is adapted to apply ground to the circuit and +50 volts to any test terminal in the system.

Whenever any one of these keys IK1 or IK2 or relays IR1—4 is operated, positive battery of 40 to 50 volts is applied to the test conductors of the connection that has been built up from the calling line through the exchange to the respective position. Through a positively polarized rectifier S+ and a resistance R, this potential is applied to a common starting relay Gs7.

Assuming, for instance, that line 599 has been

extended through a first line finder, a second line finder and a first group selector, to the wire chief's position, when the key IK1 is actuated, +48 volts will be connected through the *t* wires of the first group selector and the second line finder and then through S+3, R3 and GSR2 to ground. Similarly, the test set may be connected to the test wire of a final selector and when key IK2 is operated, +50 volts is applied through this key and then through the penultimate, fourth, third, second and first group selectors, the second line finder, S+1, R1 and GSR1 to ground.

When GSR2 operates, it closes an energizing circuit from ground over its armature and front contact and the winding of power magnet P15 and the left hand back contact and armature of relay TR5 to grounded battery. The power magnet P15 will control the movement of the brushes of the #5 first identification finder to hunt for the *t* wire of the calling line, the terminals of this switch being multiplied to the test wires of lines Nos. 500-599 and thus to the test terminals of the first line finders serving this group of lines. When the calling line is found, a circuit is closed from ground over the winding of relay TR5, the left hand back contact and armature of relay AR5, TB5, the terminal in the first identification finder and in the first line finder of line No. 599 and the brush of the operated first line finder to the +48 volt battery connected thereto by the second LF from the wire chief's key IK1. Relay TR5 opens the circuit of magnet P15 and thus stops the first identification finder brushes. Over its right hand armature and front contact, this relay closes an energizing circuit for the relay AR5 which locks up to the ground applied by relay GSR2. Through its front contact, the relay AR5 connects TB5 of the first identification finder to its assigned terminal in the banks of the second identification finders, in the present case *t*2.

If the second toll trunk were selected by a line, e. g. #500, then upon the operation of the toll identification relay IR2, GSR2 would be operated from +44 volts over S(+1) and R1. Should this happen after the key IK1 is operated, then the circuit of the clutch magnet P15 will be opened by TR5 when brush TB5 reaches the first T terminal to which battery is applied. Since there is only one first identification finder per hundred lines, no double connection can take place. The toll call on line 500 must wait for the identification of the line 599, which will happen in two to four seconds. Should the key IK1 and relay IR1 of the first toll trunk be operated simultaneously, then both relays GSR1 and GSR2 will be operated and will cause their associated first identification finders to hunt simultaneously. Each of these will select the calling T terminal in its bank. The #1 second identification finder will then pick up the first identification finder to which +48 volts was connected by key IK1 and the #2 second identification finder will pick up the first identification finder to which +48 volts was applied by relay IR1. This is so because as will presently be described, each second identification finder can stop only on a predetermined potential applied to its terminals.

Fig. 2 shows a typical control circuit for the second identification finders. All these circuits are alike except that as indicated in Fig. 1, they are connected to the ground contacts of a different key IK or a different relay IR. The only difference between the various circuits is that in each the battery marked +N volts has a differ-

ent voltage. The voltage of this battery is given in the dotted square appearing adjacent to the second identification finder brushes in Fig. 1 and corresponds to the voltage that is applied by the identification key or the identification relay to the connection. This voltage is permanently connected over a resistance R to the cathode of a three electrode vacuum tube V1 and to the grid of a similar tube V2.

- 10 When the test brush TB of the second identification finder contacts with the terminal to which the test brush of the first identification finder and the relay AR associated therewith has extended the calling test circuit, then the test potential applied to this circuit, e. g. +48 volts, will be connected over the test brush of the second identification finder to the control grid of the first tube V1 and the cathode of the second tube V2.
- 15 In the present case, upon the actuation of IK1 a circuit is closed from ground through the lower contact of the key IK1, the outer armature and back contact of relay BR and the winding of relay AR of the second I. F. to grounded battery.
- 20 The relay AR becomes energized and closes an energizing circuit from grounded battery over power magnet P of the second identification finder, the back contact and armature of relay GVR, the right hand armature and front contact of relay AR, the outer armature and back contact of relay BR to ground at the key IK1. The power magnet controls the movement of the brushes of the second identification finder #1 until the test brush thereof encounters, as above stated, the test terminal to which the key IK1 had applied +48 volts battery over the #5 first I. F. When in the control circuit of the #1 second identification finder the same potential is applied to the cathodes and the grids of both tubes, and only then, a gas valve GV will be operated. While different potentials are applied to V1 and V2 the control electrode CE of GV will be kept below ionizing potential. However, when the same voltages are applied to the two tubes, then they will not draw appreciable current and the full potential of the battery HTB will cause GV to strike, whereupon relay GVR connected to the anode A will become energized. This will open the circuit of the magnet P and stop the second identification finder brushes on the selected terminals.
- 25 The ground from key IK1 is now extended by the armature of relay GVR to the winding of relay BR which first locks up to the ground at the key IK1 and then breaks the circuit of relay AR. The gas valve GV is extinguished and the relay GVR becomes de-energized. The power magnet P cannot again become energized. The relay BR remains locked up until the identification key or identification relay is released.
- 30 Fig. 3 illustrates other applications of the invention to telephone selecting systems. Here again only the *t* wires are shown, the balance of the switching system being assumed to be of the type disclosed in my said co-pending application. In this arrangement, first and second line finders, first group selectors, special service second group selectors and toll third group selectors, are illustrated. The toll third group selectors have access to a CLR toll board and a certain number of different groups of automatic ticketing positions and out-toll trunks.
- 35 40 45 50 55 60 65 70 75
- Fig. 3 illustrates other applications of the invention to telephone selecting systems. Here again only the *t* wires are shown, the balance of the switching system being assumed to be of the type disclosed in my said co-pending application. In this arrangement, first and second line finders, first group selectors, special service second group selectors and toll third group selectors, are illustrated. The toll third group selectors have access to a CLR toll board and a certain number of different groups of automatic ticketing positions and out-toll trunks.
- A common starting relay GSR3 is connected in parallel to the *t* wires of the A links and a common starting relay GSR4 is connected in parallel to the *t* wires of the toll third group selectors.

Whenever positive potential within a broad band which, in the present case we will assume to extend from 46 to 56 volts, is applied to the *t* wire, then both these relays GSR3 and GSR4 become energized.

Assuming, for instance, that a calling subscriber dials a number which will cause the automatic switches to operate to connect his line with the CLR board, when the operator at this board actuates the identification key, she will apply +46 volts to the *t* wire causing, as above stated, the energizing of both relays GSR3 and GSR4. The first identification finder will then be operated as explained in connection with Fig. 1 to pick up the *t* wire whereupon the second identification finder, which is set for +46 volts, will pick up the first identification finder and cause the displaying of the number of the calling line on the number indicator provided at the position of the CLR operator.

GSR4 plays no role in this connection since none of the auxiliary finders is assumed to be set to operate on the application of +46 volts.

Should the CLR operator desire to introduce a repeater into the connection, she will depress her repeater key causing the application of +54 volts to the *t* wire. This again will operate both relays GSR3 and GSR4. As in the first case GSR3 will cause the first identification finder to pick up the *t* wire but since none of the second identification finders is assumed to be set to operate on +54 volts, no second identification finder will select the first identification finder. However, relay GSR4 will cause some or all the auxiliary finders to hunt for the calling *t* wires in the same manner as GSR3 did for the first I. F. The auxiliary finder marked "Repeater" is set for +54 volts (see Fig. 2) and its T brush will hunt until it encounters the *t* wire leading to the toll third group selector to which +54 volts was applied by the operator.

Obviously, each auxiliary finder has the required number of brushes and other means for controlling all the necessary switching operations. The drawings merely show a relay PR in the toll third group selector which operates when the auxiliary finder picks up this group selector to open the *t* wire towards the first line finder. This will leave the *t* wire free from the repeater to the toll operator for such subsequent use as may be necessary for the control of the repeater, e. g., to adjust the gain of the amplifier.

Obviously, an allotter may be provided to assign the auxiliary circuits, one at a time, to hunt for the call.

Should the CLR operator wish to transfer the call to another operator, e. g., at the A toll board, she may press her transfer key and apply +56 volts to the *t* wire. This will cause an auxiliary finder to extend the call to the A toll position.

The CLR operator may actuate the meter relay MR of the calling party as many times as she wishes by depressing a metering key MMK which applies -48 volts to the *t* wire. Since the meter relay is connected with the *t* wire over a negatively polarized rectifier, only it and not the relays GSR3 and GSR4 will be operated.

Assuming that the calling subscriber dials the number of a called subscriber associated with a distant exchange, and further assuming that +52 volts is applied to the *t* wire of the automatic out-trunk, the auxiliary finder marked "automatic ticketer" will connect with a toll third group selector. When this happens, it will operate the relay PR connected with this group selector which

opens the *t* wire towards the out-trunk. At the same time the automatic ticketer, by suitable means such as a relay, applies +42 volts to the *t* wire towards the calling line. Not only the first but also the second identification finder which is set to operate on +42 volts, will now operate, after which the number of the calling party is transmitted to the automatic ticketer in the same manner as described in connection with the CLR position.

Assuming in the last case that a repeater was automatically introduced upon the selection of the out-trunk by applying +54 volts to the *t* wire after having first applied +52 volts, as above described, a repeater will be automatically connected with the circuit.

Fig. 4 illustrates how this invention is applied for controlling straightforward trunking from a manual board. Each operator or group of operators has as many out-trunk jacks as are required for simultaneous out-trunk connections. In the drawings, six out-trunk groups, each group having a common trunk finder bank multiple are shown. A special potential is assigned to each trunk. The band extends from +40 volts to +50 volts. Each toll operator has a set of keys by means of which corresponding potentials may be applied to the *t* wire or sleeve of the cord. For instance, key K1 applies +50 volts, key K2, +48 volts, etc., key K6, +40 volts.

When the operator depresses the proper key and inserts the plug of her cord circuit into a free out-trunk jack individual to her position or an adjacent position, then a common starting relay GSR5 is energized over resistance R, back contact and armature of relay AR6, the sleeve wire of the jack and plug, armature and back contact of relay CR, the positively polarized rectifier S+, and say, key K3 to +46 volts. The relay GSR5 closes an energizing circuit from grounded battery over its armature and front contact and the power magnets P of all the idle trunk finders in the group to ground to hunt for the calling line. As indicated in Fig. 4, only the third group of trunk finders operates on +46 volts and therefore only this one can respond when the particular cord is reached to which +46 volts was connected, as has been explained in connection with Fig. 2. When this happens, relay AR6 is energized, opens the circuit of relay GSR5, whereupon all the unsuccessfully hunting trunk finders will stop. AR6 will apply negative battery over resistance R and its right hand front contact and armature to the sleeve of the jack and plug, whereby relay CR, which is grounded over a negatively polarized rectifier S— becomes energized and disconnects the keyset which may now be used with another cord circuit.

Obviously, the invention is applicable to many other selective or trunking schemes.

What is claimed is:

1. In combination, a first and a second switching device, a source of potentials, means for applying pairs of different potentials to said devices, each pair of potentials representing a different switching operation, means operative upon the application of any pair of potentials for actuating the first device to which one potential is applied to perform one part of the corresponding switching operation, and means for operating the second device to which the other potential of the pair is applied for performing the balance of the corresponding switching operation.
2. In combination, a first and a second group of selectively operable devices, a source of poten-

tials, means for applying a plurality of pairs of different potentials to a device in each group, each pair of potentials designating a different selecting operation composed of two steps, means operative upon the application of any potential for actuating the first group of devices to perform the first step of the selecting operation designated by the potential applied thereto, and means for operating the second group device to which the other potential of the pair has been applied to perform the second step of the selecting operation.

3. In combination, a first and a second group of selectively operable devices, a plurality of lines, a source of potentials, means for applying a plurality of different pairs of identical potentials, one to said lines and the other to the second group of devices, means operative thereupon for actuating the first group of devices to select the line to which the potential has been applied, and means for operating the second group device to which the same potential has been applied as to the line to select the operated first device.

4. In combination, a first and a second group of selectively operable devices, a plurality of lines, a source of potentials, means for applying a plurality of different potentials to said lines and second group of devices, means operative thereupon for actuating the first group of devices to connect with the line to which the potential has been applied, and means for operating the second group device to which the same potential has been applied as to the line to connect with said line over the operated first device.

5. In combination, a first and a second group of selectively operable devices, each having a bank of terminals and a cooperating set of brushes, a plurality of lines connected in multiple to the terminal banks of the first devices, a source of potentials, means for applying a plurality of different potentials to said lines and to the brushes of the second group of devices, means operative thereupon for actuating the first group of devices to connect with the terminal of the line to which the potential has been applied, and means for operating the second group device to which the same potential has been applied as to the line to connect with said line over the brushes of the operated first device.

6. In combination, a first and a second group of selectively operable devices, a plurality of lines, a source of D. C. potentials, means for applying potentials differing in voltage between predetermined lower and upper limits to said lines and second group of devices, means operative thereupon for actuating the first group of devices to connect with the line to which a potential has been applied, and means for operating the second group device to which potential of the same voltage has been applied as to the line to connect with said line over the operated first device.

7. In combination, a plurality of groups of first selectively operable devices, a plurality of second selectively operable devices, a source of potentials, means for applying different potentials from said source to one of the groups of first devices and to the second devices, each potential designating a different selecting operation, means operative upon the application of any potential to the first group for operating a first device of said group to perform the operation designated by the

potential applied, and means operative thereupon for actuating the second device to which the same potential has been applied as to the first group of devices to select the operated first device.

5. 8. In combination, a plurality of groups of lines, a plurality of groups of first selectively operable devices, one group for each group of lines, each device having a bank of terminals multiplied to the lines of the corresponding group and a set of cooperating brushes, a plurality of second selectively operable devices, each having a set of brushes and a cooperating bank of terminals to which the brushes of all the first devices are multiplied, a source of potentials, means for applying different potentials from said source to said lines and to the brushes of the second devices, means operative upon the application of any potential to a line of a group for operating the first devices of the corresponding group to operate the brushes for engaging the terminals of said line, and means operative thereupon for actuating the brushes of the second device to which the same potential has been applied as to the line to engage the terminals to which the brushes of the operated first device are multiplied.

9. In combination, a plurality of groups of lines, a plurality of groups of first selectively operable devices, one group for each group of lines, each device having a bank of terminals multiplied to the lines of the corresponding group and a set of cooperating brushes, a plurality of second selectively operable devices, each having a set of brushes and a cooperating bank of terminals to which the brushes of all the first devices are multiplied, a source of D. C. potentials, means for applying a potential of different voltages from said source to said lines and a certain voltage to the brushes of each second device, means operative upon the application of any voltage to a line of a group for operating the brushes of the first devices of the corresponding group to engage the terminals of said line, and means operative thereupon for actuating the brushes of the second device to which the same voltage has been applied as to the line to engage the terminals to which the brushes of the operated first device are multiplied.

10. In combination, a plurality of groups of lines, a plurality of groups of first selectively operable devices, one group for each group of lines, each device having a bank of terminals multiplied to the lines of the corresponding group and a set of cooperating brushes, a plurality of second selectively operable devices, each having a set of brushes and a cooperating bank of terminals to which the brushes of all the first devices are multiplied, a source of potentials, means for applying different potentials from said source to said lines and to the brushes of the second devices, means operative upon the application of any potential to a line of a group for operating the brushes of the first devices of the corresponding group to engage the terminals of said line, and means operative thereupon for actuating the brushes of the second device to which the same potential has been applied as to the line to engage the terminals to which the brushes of the operated first device are multiplied.

GERALD DEAKIN.

CERTIFICATE OF CORRECTION.

Patent No. 2,376,346.

May 22, 1945.

GERALD DEAKIN.

It is hereby certified that error appears in the printed specification of the above numbered patent requiring correction as follows: Page 1, second column, line 21, before the word "brush" insert --one illustrated in Fig. 2, is associated with the t--; and that the said Letters Patent should be read with this correction therein that the same may conform to the record of the case in the Patent Office.

Signed and sealed this 6th day of November, A. D. 1945.
